UNITED STATES PATENT OFFICE.

WILLIAM H. MERCER, OF PORTLAND, OREGON, ASSIGNOR OF ONE-HALF TO HARLEY D. FEAR, OF PORTLAND, OREGON.

BATH-TUB.

1,191,088.

Specification of Letters Patent. Patented July 11, 1916.

Application filed July 23, 1915. Serial No. 41,600.

To all whom it may concern:

Be it known that I, WILLIAM H. MERCER, a citizen of the United States, and a resident of Portland, county of Multnomah, and

5 State of Oregon, have invented a certain new and useful Improvement in Bath-Tubs, of which the following is a specification.

This invention relates generally to bath tubs, and has particularly to do with the 10 construction of a bath tub, the body of which is formed with a basin-like recess to be used for foot bathing.

Prior to my invention, bath tubs were formed wholly for body-bathing, no 15 provision being made for foot bathing, and the result was that when a foot-bath only was desired, it was necessary to use the entire body of the tub.

Therefore, one of the main objects of my 20 invention is to provide a bath tub with a basin-like recess in its bottom to be used for foot bathing.

Another of the objects of my invention is to provide this recess with an independent 25 overflow which may be closed when the bath tub is to be used for a body-bath.

The features of my invention are all fully 30 set forth in the accompanying drawings, in which—

30 Figure 1 is a longitudinal vertical section of a bath tub taken approximately on the line 1—1 of Fig. 2. Fig. 2 is a transverse vertical section of the tub taken approximately on the line 2—2 of Fig. 1. Fig. 3 is 35 a larger scaled elevation of the overflow valve shown in Fig. 2, and, Fig. 4 is a vertical section taken approximately on the line 4—4 of Fig. 3.

40 *a* represents the body of a bath tub mounted on the legs *b*.

The usual overflow is indicated by *c*, and the drain pipe is indicated by *d*, both overflow and drain pipes emptying into the waste pipe *e*.

45 The water inlet pipe is indicated by *f*, and the fixture *g* located in the bath tub is of the usual type.

In the lower end of the bath tub body *a* is a basin-like recess *h*, the rim of which is 50 rounded off where it connects with the body of the bath tub. The bottom of the recess *h* is made with a low point, and the drain pipe *d*, connects with the recess at this low point.

Said drain *d* is used for draining either the recess *h* or the body *a*, and may be closed by 55 the usual form of rubber plug *d'*.

An overflow pipe *j* connects the waste pipe *e* with the upper portion of the recess *h*.

The valve controlling the flow through the pipe *j* is of novel construction as detailed in 60 Figs. 3 and 4, and is made substantially as follows:

A plate *k* provided with a plurality of arcuate holes *l*, and circular slot *t*, is fixed in the end wall of the bath tub as shown in Fig. 4.

A bell *m*, is then fixed to 65 the outer-side of the plate *k*, and the overflow pipe *j* is connected to said bell.

A plate *o* is fixed on a headed pivot stud *p* which is rotatably mounted centrally in the fixed plate *k*.

An expansion spring *q* is inserted over the stud between the head of the latter, and the plate *k*, and forms the means by which the rotatable plate *o* is held 70 tightly against its seat on the fixed plate *k*.

A lug *o'* on the plate *l* provides a convenient 75 means for rotating the latter. The plate *o* is also provided with a plurality of arcuate holes *r* and these latter are adapted to register with the holes *l* of the fixed plate *k*, and has fixed on its inner side a stud *s*, which 80

engages with the slot *t* of the fixed plate *k*.

When a foot bath is to be taken, the overflow pipe *j* is opened by rotating the plate *o* 85 counterclockwise to the position shown in Figs. 3 and 4.

When the stud *s* strikes the end of the slot *t*, the holes *l* and *r* will be 90 in registration, and the water will overflow freely through the pipe *j*.

When the tub is to be used for a body bath, the plate *o* is rotated clockwise until the stud *s* contacts 95 with the other end of the slot *t*, and at this point the holes *l* and *r* will be out of registration, and by reason of the tight contact of the plate *o* upon the plate *k*, said overflow will be effectually closed.

I claim:

In a bath-tub provided with a basin-like depression in the bottom, said basin provided with a stoppered outlet in the bottom, an auxiliary outlet located in a side of the 100 basin, and near the top thereof and below the bottom of the main body of the bath-tub, and means for closing said auxiliary outlet.

WILLIAM H. MERCER.
